DISPLAY DEVICE

Ralph J. Mancuso, Brooklyn, N. Y., assignor, by
mesne assignments, to Carl Percy, Inc., New
York, N. Y., a corporation of New York

Application June 1, 1935, Serial No. 24,470

17 Claims. (Cl. 40—126)

The present invention relates to display devices for displaying merchandise, and more particularly to display devices for shop windows adapted to simulate a group of cartons or packages.

In arranging a window display, it is customary to stack cartons or packages of merchandise to form displays thereof to attract prospective purchasers. Where original packages are used, a substantial quantity of merchandise is required and considerable time is necessary to arrange the merchandise to best advantage. Many products deteriorate rapidly when placed in display windows and have to be sold as inferior packages or be thrown away. To eliminate these difficulties, manufacturers have designed display devices made from cardboard and the like, which simulate a group of packages of a particular product, arranged in pyramidal or other desired forms. Such devices have superseded, to a great extent, the use of original packages for display, for the reasons noted above. The present types of display devices, however, are complicated in construction, due to the number of parts utilized and to the number of attached or glued portions. In addition, such devices are customarily shipped in collapsed or flat condition and have to be rearranged into display position when placed in a window. The devices used heretofore have a number of tucked in portions, somewhat similar to the ends of a carton containing a tooth paste tube, which have to be tucked in to hold the device in display position. When it is desired to collapse the device, these tucked in portions and other parts have to be removed or rearranged, requiring considerable time and effort.

The present invention aims to overcome these difficulties by providing a simple and inexpensive display device which is constructed of a minimum number of parts and which can be quickly assembled in the manufacture thereof. In addition, the device may be instantaneously changed from a flat or collapsed position to a display position by simple folding operations and may be turned to its flat position by equally simple folding operations, thereby minimizing the time and skill required in arranging displays.

An object of the invention is to provide an attractive, inexpensive display device.

Another object of the invention is to provide a display device adapted to be made by simple cutting and creasing operations.

Another object of the invention is to simplify the manufacture of display devices by minimizing

the number of parts and by simplifying the assembly thereof.

Another object of the invention is to eliminate or minimize the numerous tucked in portions commonly found in display devices.

Another object of the invention is to provide a display device which can be readily set up by a simple folding operation and collapsed into a substantially flat condition by an equally simple folding operation.

A further object of the invention is to provide a collapsible display device which can be readily folded into a substantially flat condition to facilitate packing and shipping.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein—

Fig. 1 is a perspective view, showing a preferred embodiment of the invention, with a portion broken away to illustrate the interior thereof;

Fig. 2 is a sectional view along the line 2—2 of Fig. 1, with portions in elevation to illustrate details thereof; the dotted position illustrates the movement of the parts through the first stage of the collapsing operation;

Fig. 3 is a top plan view illustrating in full lines the parts at the end of the first stage of the collapsing operation and illustrating, in dotted lines, the device in its final collapsed position;

Fig. 4 is an exploded view, taken from the back of the device, illustrating the assembly thereof;

Fig. 5 is a front view of the main display sheet before it is assembled;

Fig. 6 is a fragmentary view illustrating details of the device;

Fig. 7 is a fragmentary perspective view illustrating a modified form of device;

Fig. 8 is a perspective view illustrating another modification of the invention; and

Fig. 9 is a sectional view taken along the line 9—9 on Fig. 8.

Described generally, the present invention contemplates the construction of a display device, the essential parts of which are made from two

sheets of material, adapted to simulate various shapes of packages and various groupings thereof, one of which is illustrated in Fig. 1 of the drawings. In the operation of the device, the simulated stacks of articles rest upon the base of the device while on display. When it is desired to collapse the device, it is merely necessary to unfold the base of the device, in which case the pyramid or simulated group of packages passes through the upright sheet of material to the other side thereof or, stated in another way, the upright sheet of material, when the base thereof is straightened out into the plane of the upright sheet, moves from the plane of the back of the pyramid to the plane of the front of the pyramid. When in the latter position, the pyramid may be folded diagonally to make a flat package. When the base is in folded position and the upright sheet is in the plane of the back of the pyramid, the display is substantially rigidly supported in position.

Referring to the drawings, and more particularly to Fig. 1 thereof, there is shown a preferred embodiment of the invention, wherein an upright sheet 1, with an integral folded base 3, serves as a support for a stack of packages which we shall term herein a "pyramid", it being understood that this term is intended to include various simulated groupings of packages, whether in the form of a pyramid or otherwise. The pyramid, as illustrated, comprises a lower portion 4 shaped and lined to simulate eight packages or cartons laid on their sides end to end in groups of fours. Above the portion 4 is a second or middle portion 5 lined and shaped to simulate ten packages standing on their ends. A third or top portion 6 is lined and shaped to simulate six packages, in vertical position, forming the top of the pyramid. In a window, such a display has the appearance of actual cartons stacked in the relation shown. While the illustration in the drawings merely designates the outline of the packages, it will be understood that in actual manufacture the sheet 1 is lithographed or printed to conform to the usual carton design. It will also be understood that while three groups of packages are simulated in the preferred embodiment, the invention contemplates displays with any desired number of groups and with various arrangements and shapes of packages.

Referring more particularly to Figs. 1, 2 and 3 of the drawings, it will be noted that the display is formed essentially from two sheets of material such as cardboard, the second or back sheet 2 being shown more particularly in Fig. 4 of the drawings, where the two sheets 1 and 2 are shown in an exploded view. The upright or front sheet 1 is cut and folded to provide the base 3 and the tops and fronts of each of the simulated groups of articles numbered 4, 5 and 6.

Referring more particularly to Figs. 4 and 5, there are shown three slotted portions 7, 8 and 9 on one side of sheet 1, and corresponding slotted portions 7', 8' and 9' on the other side thereof. These slotted portions form, respectively, the vertical and horizontal end edges of the groups of articles 4, 5 and 6, each slotted portion being adapted to form a top and side edge portion of a single group. In order to permit the sheet to be folded into display position, there are a number of score lines, indicated by dot and dash lines. The heavy portions of the dot and dash lines indicate slits intended to weaken the score lines to make it fold more readily. It will be understood, of course, that continuous scoring or creasing can

be used, if desired. The bottom front edge of the pyramid that is, the lower edge of the portion 4, is formed by the score line 10. The rear corner of the base 3 is formed by the score lines 11 and 11', and preferably the side edges of the base are reinforced by suitable tabs or flaps 3' (Fig. 3) adapted to be folded and secured to the under side of the base. While these tabs are not essential, they prevent deformation of the side edges of the base during use. The tops 13 and 13' of the ends of portion 4 are formed by the score lines 12 and 12' and 14 and 14'. Likewise, the tops 19 and 19' of the ends of portion 5 are formed by the score lines 15 and 15' and 16 and 16'. The top 20 of the pyramid is formed by the score lines 17 and 18. By comparing these reference characters, as shown in the flat sheet in Fig. 5 and in the perspective view of Fig. 1, the folding operations will be clear. It will be helpful to keep in mind that the sheet 1 forms the entire visible portion shown in Fig. 1, excepting the end portions 21, 22 and 23 of the simulated groups of cartons 4, 5 and 6 thereof.

The construction of sheet 2, forming the back of the pyramid and the sides or ends 21, 22 and 23 of the simulated groups of packages, is shown more particularly in Fig. 4, where the parts are shown bent in position to be assembled with and glued to the upright sheet 1, it being understood that a flat sheet is cut into the desired shape and scored so that it can be bent into the shape shown in Fig. 2. The upright portion 24 of sheet 2 forms the back of the pyramid and the folded portions 21, 22, 23, and 21', 22' and 23' form the ends of the simulated groups of cartons 4, 5 and 6. The flaps 26, 27 and 28 adhere to the glued portions 26', 27' and 28' of the sheet 1. In actual manufacture, the glue would preferably be applied to the members 26, 27 and 28 but, for simplicity herein, it is indicated as applied to the sheet 1. The flaps on the other side of the sheet 2 adhere to glued portions 26'', 27'' and 28''.

When sheet 2 is secured to sheet 1, as described, sheet 2 may be folded either to the left or to the right so that it will collapse along diagonal score lines to form a flat package, as shown more particularly in dotted lines in Fig. 3. When the base 3 is folded at right angles to sheet 1, the parts 13, 19 and 20 are likewise pulled into their right angled position, as shown in Fig. 1, and the upright back portion of sheet 2 moves forwardly into the plane of the upright sheet 1, while the front of the pyramid moves into the position shown in Fig. 1. With the pyramid in this position, it will be noted that it is reinforced throughout to withstand any necessary rough handling. In addition, it cannot be collapsed as long as it rests on its base because the base must be moved into the plane of the upright member 1 to collapse the display.

In order to provide additional stability and support for the pyramid, an easel 29 is cut from the back of the member 2 and folded outwardly along the score line 30, as shown more particularly in Figs. 2, 3 and 4. A suitable lock 31 for the easel is also cut out and folded outwardly along the score line 32 so that the recesses 34 and 35 engage and lock the easel in its outer position.

It will be noted that all of the parts described thus far have been constructed from two flat sheets of material. If desired, a third and smaller sheet 36 (Figs. 2, 4 and 6) may be glued to the back of the upright member 1, with the lower edge thereof projecting over the upper end of

the back of sheet 2. This auxiliary sheet 36 may be folded along the line 37 and may have recesses 38 therein adapted to receive the projections 39 on the member 2 to lock the parts in position and to hold the display device in its display position until these parts are unlatched or unlocked. A detailed view of the interlocked parts is shown in Fig. 6.

A modified form of the invention is shown in Fig. 7, wherein the parts are the same as described above, except that an additional simulated group of packages 40, here shown as two in number, is added. This additional group of packages is formed from a flat object folded as shown in Fig. 7 to form two end portions 41, which are glued to the front of the main pyramid. These glued end portions hold the additional packages in place. The upper part 42 may have a depending flap which is tucked in so that it can be removed to permit this portion to be folded about its diagonal score lines into collapsed position.

In the manufacture of the device, the sheets 1 and 2 are stamped and the sheet 2 is folded, as shown more particularly in Fig. 4. Thereafter, the flaps 26, 27 and 28 are glued to the proper parts of the back of sheet 1, which completes the formation of the essential parts of the display. Thereafter, the base 3 may be folded at right angles to the upper member 1 and the back of sheet 2 may be pressed forwardly into the plane of the sheet 1, which fixes the display in display position. The sheet 36 and its associated parts automatically lock the display in this position until released by moving outwardly the bottom part of the sheet 36. In order to collapse the display, it is merely necessary to raise the lower end of sheet 36 to release the projections 39, release and return the easel 29 to its folded position, and thereafter fold the base 3 into the plane of the upright part of sheet 1, which automatically forces the upright part of the sheet 1 forward into the plane of the front of the pyramid. Thereafter, the sheet 2, which is in extended position on the rear of sheet 1, as shown in Fig. 2, is folded along its diagonal fold lines, as shown in Fig. 2, into flat position. When thus folded, a number of displays may be packed singly or in groups, one on top of another and shipped without damage.

In Figs. 8 and 9 another modification is illustrated which comprises three groups of packages of different sizes arranged in pyramidal form. The lower group of containers comprises a top portion 45 and a front portion 46 formed from the sheet 1 and side portions provided by flaps 47 attached to the back side of the front portion. The upper group of packages comprises a top portion 48 and a front portion 49 which extends downwardly beyond the simulation of the upper group of packages and is foldably connected to the top portion 45 of the lower group. The portions 48 and 49 are likewise formed from the sheet 1 and are adapted to be folded into the plane thereof when the device is collapsed. The sides of the upper group are provided by suitable flaps 50 attached to the back of the front portion 49. These flaps preferably are connected together at the back of the device, (Fig. 9) and extend downwardly to the plane of the base portion 3. If desired, suitable outwardly extending members 51 may be formed at the lower end of the flaps 50 adapted to maintain the device in upright position and prevent tipping thereof. The intermediate group of packages preferably

is formed by a sheet 52 providing the top portion 53 and front portion 54 of the packages. Side portions or flaps 55 are foldably connected to the back of the sheet 52 and to the front of the sheet 1. The top portion 53 preferably has a cut-out part 56 therein adapted to fit about the front and the sides of the upper group so that the upper group of packages appears to be seated on the intermediate group of packages. This form of display device is particularly advantageous where a manufacturer desires to advertise a product put up in three or more sizes. The large size may be shown in the lower group, the medium size in the intermediate group and the small size in the upper group.

It will be seen that the present invention provides an attractive display which can be made from two sheets of flat material by suitable cut and scored portions. The device may be readily assembled by adhesive applied to six flaps in the construction shown herein. Thereafter, by a simple manipulation, that is, by bending the base of the upright sheet forward, the display is brought into its display position and locked in this position. By an equally simple operation, the base may be folded into the plane of the upright sheet, which permits the display to be folded along its diagonal lines into collapsed position. This eliminates the numerous tucked in parts utilized in previous constructions, and the various complicated manipulations necessary to change a pyramid from its display to its folded position and vice versa. The simplicity of the device is one of its important characteristics.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a display device, the combination of a sheet of material providing a substantially upright display wall, said wall having a portion partially cut therefrom and foldable out of the plane thereof to form the front and top walls of a display formation, and a second sheet of material foldably secured to the foldable portion of said first sheet, said second sheet forming the side walls of said display formation.

2. In a display device, the combination of a sheet of material having a base and an upright wall foldable with respect to said base, the portion of said sheet providing the upright wall having a portion partially cut therefrom simulating a plurality of articles arranged in stepped formation, said portion providing the front walls of said articles being foldable with respect to said base and upright wall, and a second sheet of material having flaps foldably attached to the back of said portion, said second sheet providing the side walls of certain of said articles.

3. In a display device, the combination of a sheet of material providing an upright display wall, said wall having a portion foldable out of the plane thereof to form the front walls of a display formation, and a second sheet of material having portions foldably secured to the foldable portion of said first sheet, said second sheet being adapted to form the side and back walls of the display formation.

4. In a display device, the combination of a sheet of material providing an upright display wall, said wall having a portion stamped there-

from and foldable out of the plane thereof to form the front and top walls of a display formation, and a second sheet of material attached to said first sheet forming the side and back walls of the display formation, said back wall having an easel portion for supporting said display device.

5. In a display device, the combination of a sheet of material having a base and an upright wall foldable with respect to said base, the portion of said sheet providing the wall having a portion stamped therefrom and foldable out of the plane thereof to simulate a plurality of articles arranged in stepped formation, said portion providing the front walls of said articles and being foldable with respect to said base and upright wall, and a second sheet of material foldably attached to said portion for providing the side walls of certain of said articles, said second sheet having a foldable easel portion formed integral therewith for supporting said display device.

6. In a display device, the combination of a sheet of material having a base and an upright wall, said upright wall and base having a foldable display formation stamped therefrom, and a second sheet of material having portions at the sides thereof foldably attached to said stamped out portion, said second sheet being adapted to provide side walls for said display formation.

7. In a display device, the combination of a sheet of material having a decorated display section, said display section having portions cut out at the sides thereof simulating the front and top walls of a plurality of articles, said display section having a plurality of folds therein to permit said portion to be folded outwardly from said wall to form the display and to be folded back into the plane of the sheet to collapse the display, and a second sheet of material foldably attached to said first sheet providing side walls for said articles, said side walls being adapted to be folded outwardly through the cut out portions of said first sheet into display position and being adapted to be collapsed when said front and top wall portions are folded into the plane of said first sheet.

45 8. In a display device, the combination of a sheet of material having a display formation partially cut therefrom and foldable out of the plane thereof, said partially cut out portion having a plurality of folds therein to permit said cut out portion to be folded outwardly from the sheet to form the front and top walls of the display formation, and a second sheet of material providing side and back walls for the display formation and foldably mounted on the back of the cut out portion of said first sheet, said second sheet having a plurality of folds therein to permit said side walls to be folded substantially into the plane of said first sheet to collapse the device.

60 9. In a display device, the combination of a sheet of material having a foldable portion forming the front and top walls of a display formation, a second sheet of material foldably attached to the back of the front walls of said first sheet and forming the side walls of said display formation, said second sheet having projections thereon, and a latch member on said first sheet for engaging said projections to lock the display device in assembled position.

70 10. In a display device, the combination of a sheet of material having a base and an upright wall foldable with respect to said base, said sheet having a portion partially cut therefrom simulating a plurality of articles arranged in stepped formation on said base, said portion providing the

front walls of said articles being foldable with respect to said base and upright wall, a second sheet of material foldably attached to said portion for providing the side walls of certain of said articles, said second sheet having projections thereon, provided with a recess, and means on said first sheet adapted to extend into the recesses of said projections to lock the display device in assembled position.

11. In a display device, the combination of a sheet of material having a base and an upright wall foldable with respect to said base, said sheet having a portion partially cut therefrom simulating a plurality of articles arranged in stepped formation, said portion providing the front walls of said articles being foldable with respect to said base and upright wall, a second sheet of material foldably attached to said portion for providing the side walls of certain of said articles, and a third sheet of material foldably attached to the front of said first sheet, said third sheet being adapted to be folded to simulate one or more articles.

12. In a display device, the combination of a sheet of material having the front and top walls of a group of cartons arranged in display formation simulated thereon, said front and top walls being foldably connected together, and said top walls being foldably connected to said sheet, said sheet being slotted to define the side edges of the top and front walls of certain cartons, whereby said top and front walls may be folded outwardly as a group from the plane of the sheet to simulate the respective wall portions of the cartons, and a second sheet of material having a plurality of portions foldably attached to the display formation of said first sheet and having portions forming the side walls of the articles when the wall portions of said first sheet are folded outwardly.

40 13. In a display device, the combination of a sheet of material having the front and top walls of a group of cartons arranged in display formation simulated thereon, said front and top walls being foldably connected together and said top walls being foldably connected to said sheet, said sheet being slotted to define the side edges of the top and front walls of certain cartons, whereby said top and front walls may be folded outwardly as a group from the plane of the sheet to simulate the respective wall portions of the cartons, and a second sheet of material attached to said first sheet, said second sheet having a back portion provided with means at the bottom thereof for supporting the display device and having portions forming the side walls of the cartons of the display, said side walls being adapted to be projected outwardly through said slits in said first sheet and to fit against the side edges of the top and front walls when said top and front walls are folded outwardly.

45 14. In a display device, the combination of a sheet of material having the front and top walls of a group of cartons arranged in display formation simulated thereon, said front and top walls being foldably connected together and said top walls being foldably connected to said sheet, said sheet being slotted to define the side edges of the top and front walls of certain cartons, whereby said top and front walls may be folded outwardly as a group from the plane of the sheet to simulate the respective wall portions of the cartons, and a second sheet of material attached to said first sheet, said second sheet having a back portion and portions forming the side walls

40

45

50

55

75

of the cartons of the display, said side walls being foldably connected to the back portion and the front walls of the cartons whereby said second sheet may be folded diagonally into substantially flat condition, said side walls being adapted to be projected outwardly through said slits in said first sheet and to fit against the side edges of the top and front walls when said top and front walls are folded outwardly.

10. 15. A foldable display pyramid, comprising the combination of a sheet having an upright wall slitted to provide the front and top walls of at least two groups of articles arranged in stepped relationship, the top wall of each of said groups being foldably connected to said upright wall of said sheet, means providing the sides of the articles foldably connected to the back of the front walls of the articles provided by said sheet, the lower edge of the upper group of articles being foldably connected to the top wall of the lower group of articles, and the lower edge of the lower group of articles being foldably connected to said sheet.

16. In a display device, the combination of 25 a sheet of material providing an upright wall

having portions simulating the front walls of a plurality of articles, cut out therefrom and foldable therewith, said articles being arranged in stepped formation to provide an upper group and a lower group, a second sheet of material foldably attached to said first sheet forming the side walls of certain of said articles and a third sheet of material extending about the lower portion of said upper group of articles in stepped relation and foldably attached to the front of said first sheet to provide an intermediate group of articles.

17. In a display device, the combination of a sheet of material providing an upright display wall, said wall having portions partially cut therefrom and foldable out of the plane thereof to provide portions of at least two walls simulating a plurality of articles arranged in stepped formation with respect to the sides of the device, and a second sheet of material foldably attached to the back of the portion foldable out of the plane of said first sheet and forming a third wall for certain of said articles.

RALPH J. MANCUSO. 25
